WINDOW CONSTRUCTION

Roy T. Axe, Syracuse, N. Y., assignor to The O. M. Edwards Company, Inc., Syracuse, N. Y., a corporation of New York

Application June 13, 1944, Serial No. 540,026

1 Claim. (Cl. 20—54)

1

This invention relates to window constructions, particularly such constructions as are used in vehicles, as buses, railway cars, etc., and has for its object a particularly simple, weather-tight and rattle-tight sliding joint between the sash, which is capable of being raised and lowered, and the sash guide. More specifically it has for its object a weather strip of resilient and yielding material, preferably fibrous material as braided and/or molded fiber, U-shaped in general form and embracing a rib on one of the two slidably engaging members and anchored thereto at the base of the rib, bulging at its sides and intermediate portion away from the sides and edge of the rib to press against the sides and the bottom of the channel in the other of the two sliding members into which channel the rib extends, whereby the sash is weather-tight, anti-rattling and also may be readily raised and lowered. The weather strip also provides a resilient mounting which compensates for inaccuracies and misalignments without interfering with the working or raising and lowering of the sash.

The invention consists in the novel features and in the combinations and constructions hereinafter set forth and claimed.

In describing this invention, reference is had to the accompanying drawings in which like characters designate corresponding parts in all the views.

Figure 1 is a fragmentary elevation of a sash embodying this invention.

Figure 2 is a sectional view taken on the plane of line 2—2, Figure 1.

Figure 3 is a transverse sectional view through the stile of the sash showing the weather strip in normal position before being compressed in the channel of the sash guide.

In the illustrated embodiment of my invention, the sash guide or frame is formed with the channel and the sash on the edge of its stile formed with the rib extending into the channel, which rib is embraced by the weather strip.

1 designates the stile of the sash and 2 the upright or body of the sash guide at each side of the sash, the sash guide being in the form of a channel, one side 3 of which is removable and constitutes a window stop. The guide 2 is secured to the post structure 4 of the car body in any suitable manner. The bottom 5 of the channel is resiliently pressed outwardly as by suitable springs, as 6, to have a follow-up movement, and a self-adjusting movement to conform to misalignments out of the vertical of the post of the car structure. The construction of the sash guide

member with the spring-pressed bottom and the removable stop portion per se forms no part of the invention. The window stop 3 is also in the form of a channel and provided with a rack 7 in the channel thereof for coacting with the pawl 8 of a sash holder 9 mounted on the bottom rail 1^a of the sash on each end of the bottom rail, the pawl being operated by a suitable lever 10. The window stop is detachably secured to the body of the sash guide body in any suitable manner, as by projections 11 extending through slots in the opposite portion of the main body of the sash guide and interlocked therewith by vertical movement of the stop 3. These projections 11 are in the form of hooks having vertically extending bills which extend through slots in the opposing surface of the sash guide 2, and then upon a vertical movement of the stop 3 interlock or come into hooking engagement with the lower end walls of the slots. This feature forms no part of the invention and is similar to that shown in Axe Patents Nos. 2,329,238 issued September 14, 1943 and 2,090,321 issued August 17, 1937.

25 The stile 1 of the sash is formed with a rib 12 extending along the edge thereof for entering the channel of the sash guide 2 or between the window stop 3 and the opposing flange or wall of the body of the sash guide 2. 13 designates a weather strip of resilient fibrous material, as a braided or woven somewhat stiff but flexible material, capable of withstanding wear, U-shaped in general form and embracing the rib, it being anchored at its edges to the stile 1 along the base of the rib and having its side and intermediate portions 14, 15 tensioned to normally bulge away from the sides of the rib and press against the opposing walls of the channel 2, that is, against the stop 3, and the flange opposed thereto and away from the lengthwise edge of the rib to press against the bottom of the channel. When so arranged in the channel, the weather strip will approach a position similar to that shown in Figure 2. Due to the inherent tension to bulge therein, it will press against the side walls and the bottom of the channel and thus form a weather-tight and anti-rattling joint. As will be understood, the spring-pressed bottom of the channel compensates for misalignments out of the vertical and of the sash guide member 2, due to the posts 4 on opposite edges of the sash not being parallel. The edges of the weather strip 13 are here shown as anchored to the stile 1 by having its opposing margins seated in grooves at 16 in the base of the rib 12, the

side walls of the groove being distorted inwardly, after the margins have been inserted in the groove.

The sash and the sash guide or the body thereof as well as the window stop are here shown as formed by extruding process, although they may be formed in any other well known manner.

By reason of this resilient weather strip located to bulge as set forth and to compress when in a channel, a sash may be made weather tight and anti-rattling in a simple and economical manner.

What I claim is:

A window construction comprising a sash guide formed with a channel having a movable resiliently pressed bottom, and a sash having a rib extending into the channel, the bottom of the channel having a follow-up movement toward the end edge of the rib, and a weather strip U-shaped in general form and embracing the rib, the strip being anchored to the sash at the base of the rib having its side and intermediate por-

tions normally tending to bulge outwardly from the sides and end edge of the rib to coact with the sides and bottom of the channel, whereby the pressure of the bottom of the channel against the intermediate portion of the weather strip tends to bulge the sides and the compression of the sides of the strip between the walls of the channel tends to bulge the intermediate portion of the strip against the bottom of the channel.
